(57) **CLAIM**

The ornamental design for a putter with removable weights, as shown.

DESCRIPTION

FIG. 1 is a front perspective view of a putter with removable weights according to my invention;

FIG. 2 is a rear perspective view of my design with the weights removed;

FIG. 3 is a front elevation view of my design of FIG. 1;

FIG. 4 is a rear elevation view of my design of FIG. 1;

FIG. 5 is a right side elevation view of my design of FIG. 1;

FIG. 6 is a left side elevation view of my design of FIG. 1;

FIG. 7 is a top plan view of my design of FIG. 1;

FIG. 8 is a bottom plan view of my design of FIG. 1;

FIG. 9 is an exploded front perspective view of my design;

FIG. 10 is a front perspective view of a weight of my design of FIG. 9;

FIG. 11 is a top plan view of the weight of my design of FIG. 10; and,

FIG. 12 is a bottom front perspective view of my design of FIG. 1.
